CLAIM

The ornamental design for a foldable bottle for containing liquids, as shown and described.

DESCRIPTION

FIG. 1 is a front perspective view of the foldable bottle for containing liquids, showing my new design;

FIG. 2 is a front elevational view thereof;

FIG. 3 is rear elevational view thereof;

FIG. 4 is a top plan view thereof;

FIG. 5 is a bottom plan view thereof;

FIG. 6 is an expanded bottom plan view thereof;

FIG. 7 is a left side plan view;

FIG. 8 is a right side plan view; and,

FIG. 9 is a front perspective view, the broken lines illustrate a clip for use with the bottle for containing liquids and form no part of the claimed design.
